UNITED STATES PATENT OFFICE

HENRY G. LYKKEN, OF MINNEAPOLIS, MINNESOTA

METHOD OF AND MEANS FOR FIRING KILNS

Application filed August 28, 1926. Serial No. 132,062.

The present invention relates to the firing of kilns, and the like, such as the type in which the ware to be fired may be moved past the firing point or points.

5 Among the objects of the invention are to provide a novel method of firing kilns with powdered or pulverized fuel, it being broadly new to use such fuel for firing kilns. It is preferable to apply the heat at 10 different points or loci and to independently control the firing at each locus for the desired heat treatment to be effected at such locus as the ware passes through or by the same.

15 Another object is to provide for igniting and maintaining ignited the pulverized fuel as it is supplied to each firing chamber or locus, and preferably to vary the fuel either in quantity or character, or both, as by 20 varying the proportions of the powdered fuel and the supporter of combustion, such as air, or by the introduction of additional air, such introduction being regulated or controlled as to the amount introduced. The 25 ignition may be effected by maintaining a quantity of incandescent fuel in the chamber toward which, as by downward direction, the powdered fuel and air may be supplied or directed, the complete combustion of the 30 powdered fuel being effected in the chamber and above the incandescent fire bed or the like in the chamber. Means may be used to maintain this bed in incandescence. The term "incandescent" or "incandescence" is 35 used herein to comprehend low degrees of incandescence or glowing as well as any higher degrees.

Another object is to supply the powdered fuel from preferably a common source and 40 to supply the same, such as by means of blowers or aspirators or the like, to each firing locus or chamber independently, and also to vary each independently as by the introduction of additional air into the combustible mixture to effect a leaner mixture 45 or to vary the amount of heat developed by the combustion in the chamber. In this way absolute control of the heat at each locus is possible, as also the supplying of the required heat at each point which might re-

quire more or less than at other points. In the burning of many wares, it is desirable to vary the character of the atmosphere or gases surrounding the ware, such as the producing of reducing conditions at certain 55 points and oxidizing conditions at others. Where the effects of the direct rays of combustion would be undesirable, screening may be resorted to by the interposing of a screen of checker work or the like between each 60 chamber and the passage for the ware.

Other objects, capabilities, advantages and features are comprehended by the invention as will later appear and are inherently 65 possessed thereby.

Referring to the drawings, Fig. 1 is a fragmentary top plan view of a tunnel kiln constructed in accordance with the invention.

Fig. 2 is a transverse sectional view of the 70 same and a firing chamber, with parts shown in end elevation.

And, Fig. 3 is a longitudinal view taken in a vertical plane through a firing chamber.

Referring now more in details to the 75 drawings, the embodiment selected to illustrate the invention is shown as comprising a kiln tunnel 1 through which may travel cars 2 upon tracks 3 and carrying ware 4 upon the cars. The passage or tunnel is 80 preferably covered with a suitable roof 5 of any kind of refractory material or the like. At each side of the tunnel or passage are located a number of chambers 6 and 7 at different points, each chamber having 85 communication with the tunnel passage and having a firing space or chamber 8 within each of the chambers. A screening device as in the form of checker work 9 may be provided between the chamber 8 and the 90 passage of the tunnel.

Within each chamber may be located a 95 grate or other like support, or a perforated floor 10 upon which may be located a fire bed 11 of suitable fuel and which is to be maintained in more or less incandescent or glowing state. For the purpose of effecting the incandescence of the fire bed, means may be provided for the supply of a supporter of combustion beneath the grate 10, 100

such means being, in the embodiment shown, shown as comprising as air duct 11^a, an air pipe 12 leading into a subchamber 13 beneath the grate 10, the entry of the air 5 through the pipes 12 being controlled by suitable valves 13' which may be operated to adjust the amount of air supplied to the fire bed. For the purpose of supplying fuel upon the grate 10, the furnace may be provided with a charging door or opening 14 10 having a closure 15 which is normally maintained closed, but opens when new fuel is placed upon the grate 10.

At the upper part of the chamber 8 is provided a discharge conduit 16 connected to a rotary blower or fan 17 suitably driven as by a belt 18 in turn driven by a shaft 19 and 20 operatively supported above the top of the furnace, as clearly shown in Fig. 20 1 of the drawings.

Leading to each blower 17 is a fuel duct 21 each leading to and being conducted to a common fuel supply duct 22 which may be connected to any suitable means for supplying powdered fuel and air in desired proportions, preferably in uniform proportions or mixture, as desired.

In the operation of the device the trucks or cars 2 are caused to travel through the 25 kiln with the ware 4 thereupon and pass the checker work 9 of the firing chambers or furnaces. Assuming that the fire bed or fuel 11 has been brought to an incandescent state, and the door 15 is closed, as 30 well as the valve 13', or the same left partially open, to maintain incandescence of the fire bed, the blowers are operated to draw a mixture of powdered fuel and air through the duct 21 to the fan or blower 17 and to 35 discharge such mixture through the conduit 16 downwardly through the upper part of the chamber space 8 and toward the fire bed 11. The latter, by reason of being in the incandescent state, will ignite this fuel 40 and cause the same to be burned completely within the fire chamber 8, the hot products of combustion, then passing through the checker work into the tunnel space and 45 through and among the ware.

Each blower 17 is preferably provided with one or more air inlet openings 23 adapted 50 to be controlled by a shutter or the like 24 of any suitable construction, such that the latter may be adjusted to either partially open, completely open or close the apertures or openings 23 for regulating the amount of 55 additional air that may be introduced into the mixture in the fan in order to provide a more or less lean mixture of the combustible material as it is projected into the combustion chamber 8.

It is to be understood that the ware in 60 passing through the tunnel, to be properly treated, should be affected with heat conditions in different amounts and in differ-

ent character, as the ware proceeds. At some points the combustion is so effected that a reducing action may be effected at the locus or loci of the passage of the ware adjacent such firing chambers. At other 70 places an oxidizing condition or action may be effected. By providing independent blowers for each furnace, or firing chamber, and independent means for controlling the inlet of air or the like into the fans, the 75 particular type of combustion desired may be effected.

If desired, each conduit 21 may be provided with a control valve 25 which may be operated in any suitable manner to more or less restrict the passage of the mixture through the conduit 21 to the respective blower connected thereto. From the above it will be apparent that not only the total quantity of the combustible mixture passing from the conduit 21 to the fan may be regulated, but its character may also be varied by the introduction of air through the openings 23 in a variable or regulatable manner.

While I have herein described and upon the drawings shown one embodiment of the invention, it is to be understood that the invention is not limited thereto nor to the particular process steps described, but that 95 it may comprehend other features, details, constructions and arrangements of parts as well as other process steps without departing from the spirit thereof.

Having thus disclosed the invention, I 100 claim:

1. The method of firing consisting of maintaining a quantity of fuel in incandescent state, supplying a fluidal mixture of pulverized fuel and air, and burning said 105 mixture, said incandescent fuel acting to ignite and maintain ignited said mixture.

2. The method of firing, comprising maintaining an incandescent fuel bed at a low point, and projecting a stream of mixed 110 pulverized fuel and air downwardly toward said bed.

3. The method of firing, comprising maintaining an incandescent fuel bed at a low point, projecting a stream of mixed pulverized fuel and air downwardly toward said 115 bed, causing said fuel in said stream to burn, and screening the radiant rays of said burning fuel from ware being fired.

4. The method of burning fuel comprising the supplying of mixed pulverized fuel and air downwardly upon a fuel bed, and maintaining said fuel bed in incandescent state.

5. A firing device, comprising a common source of mixed pulverized fuel and air, a plurality of firing chambers located at different loci, means for supplying said mixed fuel and air from said source to each of said 120 125 said chambers.

- chambers, and means for regulating the supply at each of said chambers.
6. A firing device, comprising a common source of mixed pulverized fuel and air, a plurality of firing chambers located at different loci, means for supplying said mixed fuel and air from said source to each of said chambers, and means for admitting additional air at said chambers.
- 10 7. A firing device, comprising a common source of mixed pulverized fuel and air, a plurality of firing chambers located at different loci, means for supplying said mixed fuel and air from said source to each of said chambers, means for admitting additional air at said chambers, and means for varying said additional air admitting means.
- 15 8. A firing device, comprising a firing chamber, means therein for supporting a fire bed, means for maintaining said bed in incandescence, means for directing a mixture of powdered fuel and air toward said bed whereby the latter may ignite the mixture and maintain the same ignited.
- 20 9. A firing device, comprising a firing chamber, means therein for supporting a fire bed, a screen between the firing space in said chamber and the ware in the kiln, and means for maintaining said bed in incandescence, means for directing a mixture of powdered fuel and air toward said bed whereby the latter may ignite the mixture and maintain the same ignited.
- 25 10. A firing device, comprising a firing chamber, means for maintaining a quantity of fuel in incandescent condition in said chamber, means for blowing a uniform mixture of pulverized fuel and air toward said incandescent fuel, means for variably introducing given amounts of air into said mixture at said chamber.
- 30 11. In a tunnel kiln having a passage for travel of ware, firing chambers at different loci at the sides of said passage and communicating therewith, incandescent means in each chamber, and means for directing a mixture of pulverized fuel and air downwardly in each of said chambers and toward the incandescent means therein.
- 35 12. In a tunnel kiln having a passage for travel of ware, firing chambers at different loci at the sides of said passage and communicating therewith, incandescent means in each chamber, means for directing a mixture of pulverized fuel and air downwardly in each of said chambers and toward the incandescent means therein, and means for varying said mixture for desired degree of firing.
- 40 13. In a tunnel kiln having a passage for travel of ware, firing chambers at different loci at the sides of said passage and communicating therewith, incandescent means in each chamber, means for directing a mixture of pulverized fuel and air downwardly
- in each of said chambers and toward the incandescent means therein, and means in each chamber for introducing additional air in desired amounts into said mixture at said chamber.
- 45 14. In a tunnel kiln having a passage for travel of ware, firing chambers at different loci at the sides of said passage and communicating therewith, incandescent means in each chamber, means for directing a mixture of pulverized fuel and air downwardly in each of said chambers and toward the incandescent means therein, means in each chamber for introducing additional air in desired amounts into said mixture at said chamber, and means for varying the amount of air so introduced.
- 50 15. In a tunnel kiln having a passage for travel of ware, firing chambers at different loci at the sides of said passage and communicating therewith, incandescent means in each chamber, means for directing a mixture of pulverized fuel and air downwardly in each of said chambers and toward the incandescent means therein, and means for screening the ware from the direct rays of heat in said chamber.
- 55 16. The method of firing consisting of the projecting of a mixture of pulverized fuel and air toward a maintained and maintainable incandescent bed of fuel, and controllably varying said projecting of the mixture as desired.
- 60 17. The method of firing consisting of the downward projecting of a mixture of pulverized fuel and air upon a maintained and maintainable bed of fuel, and controlling the mixture to the projecting means for maintaining a uniform mixture at any rate of supply.
- 65 18. The method of firing consisting of the downward projecting of mixtures of pulverized fuel and air upon maintained and maintainable incandescent beds of fuel of a plurality of fire boxes, and individually controlling the amount of mixture at each box.
- 70 19. The method of firing consisting of the downward projecting of mixtures of pulverized fuel and air upon maintained and maintainable incandescent beds of fuel of a plurality of fire boxes, individually controlling the amount of mixture at each box, and screening the fire from the ware at each box.
- 75 20. The method of firing consisting of the drawing a mixture of pulverized fuel and air from a common source where a uniform and constant mixture is maintained, and firing the mixture upon a maintained and maintainable fuel bed.
- 80 In witness whereof, I hereunto subscribe my name to this specification.
- 85 HENRY G. LYKKEN.
